Inventor

William H Tolson

UNITED STATES PATENT OFFICE.

WILLIAM H. FOLSOM, OF MINNEAPOLIS, MINNESOTA.

MECHANICAL MOVEMENT.

1,323,851.

Specification of Letters Patent.

Patented Dec. 2, 1919.

Application filed April 11, 1917. Serial No. 161,209.

To all whom it may concern:

Be it known that I, WILLIAM H. FOLSOM, a citizen of the United States, residing at Minneapolis, in the county of Hennepin and State of Minnesota, have invented certain new and useful Improvements in Mechanical Movements, of which the following is a specification.

My invention has for its object to provide 10 a simple and efficient mechanism for converting and transmitting power. It is adapted to be driven by any suitable form of prime mover, such as an electric motor or an engine, for example, and it is adapted to 15 perform various different kinds of work, such, for example, as the operation of pumps. It involves various novel combinations of devices and mechanical movements coöperatively connected and properly timed. 20 While, as above indicated, the device is capable of use to do any and all kinds of work, it is illustrated in the drawings as used to drive reciprocating pumps, and as hereinafter described, it will be referred to 25 as performing that function, but, of course, the invention is not at all limited to that particular purpose.

The device or machine is adapted to be made up of any desired number of units, and 30 in the drawings, only one of these units is illustrated.

In the accompanying drawings which illustrate the invention, like characters indicate like parts throughout the several views.

35 Referring to the drawings,

Figure 1 is a side elevation illustrating the invention; and

Fig. 2 is a plan view of the parts shown in Fig. 1.

40 The framework of the machine may be of any suitable construction, but as shown in Fig. 1, it comprises a horizontally disposed frame bar 3 having supporting legs 4 and certain other parts hereinafter to be noted.

45 The floor structure is indicated by the numeral 5. The numeral 6 indicates the cylinders of a pair of pumps, which cylinders, as shown, are pivoted to brackets 7 rigidly secured on the floor structure 5. Working 50 within the cylinders 6 are pistons having long upwardly projecting rods 8. The upper ends of the piston rods 8 are pivotally connected to the opposite ends of a walking beam 9 that is intermediately pivoted by a 55 shaft 10 to a bracket 11 that is rigid on the frame bar 3.

The numeral 12 indicates a rocker shown as of skeleton form, being, in fact, a representation of any segment of and up to a complete wheel having its axis at 13. The periphery 14 of this rocker segment 12 engages upon the upper surface of the walking beam 9. As shown, the engaging surface of the walking beam 9 and segmental surface 14 are smooth, but when desired, may have any usual anti-slipping connection as toothed engagement. When made smooth, as shown, there is a possibility of slippage, and to prevent this, spring-pressed centering rods 15 are pivotally connected to the lower portion of said rocker 12 and to the opposite end portions of the walking beam 9, and moreover, the said rocker is preferably provided with a depending centrally located fork 16 that loosely embraces the pivot shaft 10 of the said walking beam. At its upper end, and on its opposite sides, the rocker 12 is provided with laterally spaced pairs of arms 17 through which work the upper end of tension rods 18, as shown, four in number. Immediately above the arms 17, the rods 18 are provided with shoulders or stop collars 19. At their lower ends the rods 18 are connected in pairs by short rods 20, and these rods are connected to the opposite ends of a tension yoke 21, which, at its intermediate portion, has a pin 22 mounted for vertical sliding movements in a bracket 23 rigidly secured to the floor or underframe structure 5. The numeral 24 indicates a toggle, the lower arm of which is pivoted on the pin 22 and the upper arm of which is pivoted at 25 to a bracket 26 fixed to the frame 3. The upper link of the toggle 24 has a projecting arm 27 that is pivotally connected to one end of a lever 28, which latter is intermediately pivoted to a bearing 29 rigid on the floor or underframe structure 5. The outer end of this lever 28 is connected by a link 30 to one end of a lever 31 that is intermediately pivoted to the frame 3. The outer end of the lever 31 is connected by a short link 32 to the crank 33 of a driving shaft 34 that is journaled in suitable bearings on the frame 3. This shaft 33 may be either directly or indirectly connected to a prime mover. Any one of the several shafts of the machine may, in fact, be used as a driving shaft, but for the purpose of the present description, the said shaft 34 will be treated as the driving shaft. As shown, it is provided with a pulley 35 over which a power-driven belt 36 is

arranged to run. The shaft 34 carries a drive wheel shown in the form of a sprocket 37. At the opposite end of the frame 3 located parallel to the shaft 34 is a similar shaft 38 also journaled in suitable bearings on the frame 3, or elsewhere. This shaft 38 is provided with a sprocket 39 that is twice the diameter of the sprocket 37. A long sprocket chain 40 runs over the aligned 10 sprockets 37 and 39, so that the said shaft 38 will be driven at one-half the speed of the shaft 34. This is important as will presently appear. A sprocket 41 is provided from which power may be taken and the 15 shaft 38 also carries another sprocket 42. A sprocket chain 43 runs over the sprocket 42 and over a sprocket 44 on the lower shaft 45 which, as shown, is journaled in suitable bearings 46 on the floor or underframe structure 5. The shafts 38 and 45 are driven at the same speed, to wit, at one-half the speed of the shaft 34. The shaft 38 is provided with a crank 47 and shaft 45 is provided with a crank 48. The crank 48 is set ninety 20 degrees ahead of crank 47 in the clockwise direction of their respective rotations.

Crank 47 is connected by a link 49 to a lever 50 that is intermediately pivoted at 51 to a bracket 52 on the frame 3. The 30 long upper end of this lever 50 is connected by a link 53 to the upper end of the rocker 12.

The crank 48 is connected by a link 54, to the outer end of a lever 55 that is intermediately pivoted to a depending bracket 35 56 of the frame 3. The inner end of the lever 55 is connected by a link 57 to one end of the walking beam 9.

Journalled in any convenient point upon the construction is a shaft 58 carrying 40 thereon a sprocket wheel 59 and a clutch wheel 60. Over the sprocket 59 extends the sprocket chain 61, which also passes over the sprocket 41 from which power may be taken as described in relation to said 45 sprocket.

Fulcrumed also upon the shaft 58 are arms 62 and 62', carrying pivoted thereon detents 63 and 63', respectively. The detents 63 and 63' are held to work upon the 50 clutch disk 60 by means of springs 64 connected therewith at one of their ends and at their opposite ends to any convenient source.

Pivoted also to the arms 62 and 62' are 55 links 65 which in turn are pivoted to the lever 66, pivoted to any rigid abutment. The lever 66 is in turn connected by link 67 to the walking beam 9, so that as the walking beam 9 oscillates upon its pivot 60 10 as hereinbefore described, the lever 66 is oscillated upon its pivot to the dotted line position shown in Fig. 1, and to a position upon the opposite side of the full line position corresponding to such dotted line 65 position. The oscillation of this lever 66

upon its pivot through the medium of the links 65 also oscillates the arms 62 and 62' with oppositely rotative movement about the shaft 58. As the arms 62 and 62' move upwardly the detent 63' engages the cam 70 disk 60 and rotates it in the direction for rotation of all of the parts, whereas when the arms 62 and 62' move downwardly in their rotative movement the detent 63 engages such cam disk 60 and continues the 75 rotative movement initiated by the detent 63'. The disk 60 being rigidly secured to the sprocket 59, such sprocket is moved with the rotative movement of the disk, and such rotative movement of the sprocket 59 is imparted to the sprocket 41 through the medium of the chain 61.

In the machine as designed, it may be assumed that all movements of the rotary parts are clockwise, in respect to Fig. 1. Any one 85

of the three shafts 34, 38 or 45 may be used as the driving member, but, as already stated, I assume that the power is practically delivered to the so-called driving shaft 34. In Fig. 1, the full lines indicate 90

what may be called the dead center or neutral position of the rocker 12 and of the walking beam 9. Under rotation of the driving shaft 34 in a clockwise direction through one-half rotation, the shafts 38 and 95 45 will be driven in the same direction but at half the speed thereof, and under such movement, the walking beam, by movement of the lever 55, and the rocker, by movement of the lever 50, will be rocked into an oblique position at the right just reverse from that shown by dotted lines in Fig. 1. In fact, the dotted lines, Fig. 1, indicate the position of the parts after the shaft 34 has

made one and one-half rotation and the 100 crank shafts 38 and 45 have been given three-fourths of a rotation. When the driving crank shaft 34 has been given one complete rotation and the crank shafts 38 and 45 have been given one-half rotation, the 105 rocker will be again back to the position indicated by full lines in Fig. 1.

The lever connections 28, 30 and 31 are, by the crank 32, so timed and operated that the members of toggle 24 will approach 110 alinement, as indicated by dotted lines in Fig. 1, as the rocker approaches the limit of its oscillatory movement in either direction. This obviously, is because the said

toggle is given two straightening operations for each complete rotation of the cranks 47 and 48. As the toggle 24 is straightened, it pulls the yoke 21 down and presses the collars or shoulders 19 of the tension rods 18 against the arms 17 of the rocker 12, and, of course, it does this at a time when the walking beam is oscillating in the one direction or the other from its horizontal or intermediate normal position and the tension 120 thus produced, gives an augmented down-

125 position. The oscillation of this lever 130

ward force on the downwardly moving side of the walking beam. When the walking beam reaches the limit of its oscillatory movement in either direction, the toggle will 5 be completely extended, but by means of the rotation of the shaft 34 the toggle will at once relieve the walking beam from this downward pressure, thereby permitting the walking beam to be freely returned to its 10 horizontal normal position under the action of the crank 48, lever 55 and link connections, and at the same time, permits the rocker 12 to be freely restored to its vertical neutral position by the crank 47 15 through the lever 50 and link connections.

Movements of the walking beam 9, as already indicated, will be utilized to produce various different kinds of work, but in the drawings, its oscillatory movement, as above 20 described, of course reciprocates the pump pistons and operates the pumps. Of course, the two shafts 38 and 45 will be continuously driven at one-half the speed of the driving shaft 34, and the shaft 58 is further driven 25 from the walking beam 9 through the link 67, lever 66 and connections to the dog-equipped arms 62 and 62'. More specifically stated, under upward movements of the links 65 and arms 62', operating on the clutch 30 wheel 60, will rotate the shaft 58 in a clockwise direction and under downward movement of the said link 65 the dog of the arm 62 operating on the clutch wheel 60 will drive the said shaft in a clockwise direction.

35 All of the parts of the machine are driven in proper synchronism, and the toggle-actuating connections are timed in respect to the walking-beam-actuating connections and the rocker-actuated connections in the relation 40 of two to one.

Any desired number of units, such as described, may be employed and coupled up, side by side, or otherwise, in a common machine. When thus used, the corresponding 45 cranks of the several units would preferably be partly set, one ahead of the other, so as to give a uniform application of power.

What I claim is:—

1. A mechanism of the kind described 50 comprising a walking beam, a rocker having traveling engagement with said walking beam, from one side to the other of the pivot thereof, and means timed in synchronism with the oscillation of said walking beam 55 for rocking said rocker and for augmenting the weight of said rocker alternately upon the downwardly moving sides of said walking beam.

2. A mechanism of the kind described 60 comprising a walking beam, a rocker having traveling engagement with said walking beam from one side to the other of the pivot thereof; two cranks driven at the same speed and a third crank driven at twice the speed 65 of the other two; connections from one of

said slow-moving cranks for oscillating said walking beam; connections from the other slow-moving crank for rocking said rocker on the said walking beam; and connections from said faster-moving crank timed to augment the pressure of the said rocker alternately upon the downwardly moving sides of said walking beam and to relieve the upwardly moving sides of said walking beam from such augmentation of pressure. 70

3. In a mechanism of the kind described, the combination with a walking beam having connections for the delivery of power therefrom; of a rocker having traveling engagement with said walking beam from one 80 side to the other of the pivot thereof; a toggle with connections to said rocker for augmenting the weight of the same upon the downwardly moving sides of said walking beam; two cranks driven at the same speed; 85 a third crank driven at twice the speed of said first-noted cranks; connections from one of said slow-moving cranks for oscillating said walking beam; connections from the other slow-moving crank for rocking said 90 rocker, connections from said third or fast-moving crank for operating said toggle; the said parts being timed in synchronism so that said toggle will straighten to press said rocker with augmented force, alternately 95 upon the downwardly moving sides of said walking beam; and the said toggle will be flexed to relieve the upwardly moving sides of said walking beam from said augmented force. 100

4. In a mechanism of the kind described the combination with a walking beam; of a rocker superimposed thereon and having traveling engagement therewith from one side to the other of the pivot thereof; a 105 toggle having connections to said rocker for forcing the same downward with augmented pressure upon the downwardly moving sides of said walking beam; a walking-beam-actuating crank with connections for oscillating 110 said walking beam; a rocker-actuating crank with connections for rocking said rocker; and a toggle-actuating crank with connections for oscillating said toggle; and connections between said three cranks driving said walking-beam-actuating crank and rocker-actuating crank at the same speed; and driving said toggle-actuating crank at twice the speed of the other two cranks whereby the said cranks will be operated in 120 synchronism and the said toggle will straighten to force said rocker with augmented pressure upon the downwardly moving sides of said walking beam, first on one side and then on the other of its pivot. 125

5. A mechanism of the kind described comprising a walking beam; a rocker having traveling engagement with said walking beam; from one side to the other of the pivot thereof; means timed in synchronism 130

for oscillating said walking beam for rocking said rocker and for pressing said rocker alternately against the downwardly moving sides of said walking beam; and a pawl and ratchet driving device operative from said walking beam and transmitting its power to some of said crank shafts.

6. A mechanism of the kind described comprising a walking beam; a rocker having traveling engagement with said walking beam; from one side to the other of the pivot thereof; means timed in synchronism for oscillating said walking beam, for rocking said rocker and for pressing the said rocker alternately against the downward moving sides of said walking beam; and mechanism operated from said walking beam.

7. In a mechanism of the kind described, the combination with a walking beam; of a rocker superimposed on said walking beam and having a traveling movement thereon from one side to the other of the pivot thereof; a yoke; rods connecting said yoke to the upper portion of said rocker; a toggle operative to depress and raise said yoke and rods; two relatively slow-moving cranks operating at the same speed but set one ahead of the other; connections between one of said cranks and said walking beam for oscillating the same; connections between the other of said cranks and said rocker for rocking the same; and a third crank rotated at twice the speed of said first-noted cranks and having connections to said toggle for straightening and flexing the same, the said parts being driven in synchronism and so timed that said toggle will straighten to produce an augmented downward pressure of said rocker on the downwardly moving side of said walking beam, first on the one side and then on the other, the flexing movement of the said toggle serving to alternately relieve the upwardly moving sides of said walking beam from the toggle-produced pressure delivered through said rocker.

8. A mechanism of the kind described comprising a walking beam; a rocker having traveling engagement with said walking beam, from one side to the other of the pivot thereof; and means timed in synchronism for oscillating said walking beam, for rocking said rocker and for augmenting the

weight of said rocker alternately upon the downwardly moving sides of said walking beam; and a positioning device holding the said rocker properly disposed in respect to said walking beam.

9. In a mechanism of the kind described, the combination with a walking beam; a rocker superimposed on said walking beam and having a restricted traveling movement thereon from one side to the other of the pivot thereof; a yoke; rods connecting said yoke to the upper portion of said rocker; a toggle operative to depress and raise said yoke and rods; two relatively slow-moving cranks operating at the same speed but set, one ahead of the other; connections between one of said cranks and said walking beam for oscillating the same; connections between the other of said cranks and said rocker for rocking the same; and a third crank rotated at twice the speed of said first-noted cranks and having connections to said toggle for straightening and flexing the same; the said parts being driven in synchronism and so timed that said toggle will straighten to produce an augmented downward pressure of said rocker on the downwardly moving side of said walking beam, first on the one side and then on the other, the flexing movement of the said toggle serving to alternately relieve the upwardly moving sides of said walking beam from the toggle-produced pressure delivered through said rocker; and a pawl and ratchet driving device operated from the oscillation of the said walking beam.

10. A mechanism of the kind described, comprising a walking beam; a rocker superimposed upon and having a traveling movement thereon from one side to the other of the pivot thereof; means for oscillating said walking beam; means for rocking said rocker in synchronism therewith so that its weight will be thrown alternately upon the downwardly moving sides of said walking beam; and means for delivering power from said walking beam.

In testimony whereof I affix my signature in presence of two witnesses.
